HEADBOARD

Robert V. Jacobs, Los Angeles, Calif., assignor to Baby-line Furniture Corp., Los Angeles, Calif., a corporation of California

Filed May 8, 1968, Ser. No. 11,836

Term of patent 14 years

Int. Cl. D6—01

U.S. Cl. D5—4

FIG. 1

FIG. 3

FIG. 1 is a front elevational view of a headboard embodying the new design of my invention;

FIG. 2 is a side elevational view thereof; and

FIG. 3 is a top plan view thereof.

The back side of the headboard illustrated is substantially plain and unornamented.

I claim:

The ornamental design for a headboard, substantially as shown and described.
